PROTECTIVE APPARATUS

Edward A. Leach, Schenectady, N. Y., assignor to
General Electric Company, a corporation of
New York

Application August 17, 1935, Serial No. 36,752

19 Claims. (Cl. 179—171)

My invention relates to protective apparatus and more particularly to apparatus for protecting the individual units of electrical apparatus of a multi-unit system from faults while maintaining in service those units of the system which are free from fault.

While my invention is not limited thereto I contemplate its use more particularly in connection with high frequency apparatus such as carrier wave signal transmitters and amplifiers. It has for one of its objects to provide a novel and improved form of protective system for such apparatus.

In connection with high power broadcast transmitters, such as are used for radio program broadcasting, the continuity of service of the transmitting equipment is of extreme importance. If, by reason of a fault in an apparatus unit, such as an amplifier of said equipment, the transmitter cannot be continued in service at its normal rated capacity, it is important to continue it in service at lower than normal capacity. In this way a large portion of the total area served by the transmitter may be afforded service which is substantially free from interruptions due to faults in the transmitter equipment.

One of the objects of my invention, therefore, is to provide means whereby the individual units of the transmitting equipment may be disabled and removed from service in response to a fault therein while the remainder of the equipment is continued in service. Thus, for example, the transmitter provided with my invention may comprise a plurality of amplifiers, any one of which may fail at any time. In accordance with my invention means are provided automatically to remove an amplifier in which a fault develops from service and to establish connections whereby the other amplifiers are connected in operating circuit relation whereby the transmitter may be continued in service with somewhat reduced output.

A further object of my invention is to provide an improved switching scheme for effecting the various control operations necessary to attain the ends above set forth.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings in which Fig. 1 shows sche-

matically an embodiment of my invention; Fig. 2 represents a side view of a portion of the switching structure involved; Figs. 3, 4, 5, and 6 represent details thereof; and Figs. 7 and 8 represent endwise views.

Referring to Fig. 1 of the drawings, I have illustrated my invention therein in its application to a high frequency transmitter. The transmitter represented in the figure comprises a plurality of amplifiers indicated by rectangles 1, 2, 10 and 3, the output circuits of which are normally connected in series by means of a common switch means, presently to be described, to supply amplified oscillations to an antenna 4; and the input circuits of which are excited in parallel with oscillations to be amplified, which oscillations are supplied from an exciter 5. Both the input circuits and the output circuits of these amplifiers, as well as the circuits for supplying operating potentials thereto, are controlled by means of the unitary switch structure which I shall now describe insofar as this structure is illustrated in Fig. 1.

This switch comprises a shaft 6 which extends throughout the transmitter in proximity to the amplifiers which are to be controlled. This shaft has mounted thereon, and positioned along the shaft, a number of sleeves 7, 8, and 9 each of these sleeves corresponding to a respective amplifier. Each of these sleeves is arranged to be rotated about the shaft through a predetermined angle by means of its respective actuating mechanism 1', 8', 9'. Each sleeve has fixedly attached thereto a group of cross-arms 12, 13, 14, 15, 16, 17, 18, 19, 20; respectively. These cross-arms have mounted on their opposite ends conducting bridge assemblies, which are conventionally indicated by members 12', 12'', 13', 13'', 14', 14''; etc., each of which bridge members bridges a pair of stationary contacts in a corresponding stationary contact bank. The different contact banks corresponding respectively to the different cross-arms each include six contacts which will be referred to herein by the reference letters a, b, c, d, e, and f respectively as applied on the drawings to the contacts of the bank cooperating with cross-arm 12.

The switch is shown in its normal closed circuit position in which it will be observed that the conducting bridge members 12', 13', 14', etc. each bridge the contacts b and c of its respective bank, and the bridge members 12'', 13'', 14'', etc. each bridge the contacts e and f of its respective bank. The shaft 6 may be operated to the right to move all of the bridge

5

members away from the contacts with which they normally engage. Any one or more of the actuating mechanisms 7', 8', 9' may then be actuated to rotate the respective sleeves thereby carrying the bridge members of the respective section of the switch about the shaft to a position such that when the shaft is moved back to the left or to its circuit closed position the respective bridge members 12', 13', 14' bridge contacts *a* and *b* of their respective banks whereas the bridge members 12'', 13'', 14'' bridge the contacts *d* and *e* of their respective banks.

To produce this longitudinal movement of the shaft 6 it is normally biased to the right by means of a spring 22 arranged at the right end thereof, and it is restrained against movement to the right by means of a latch 23 and cam 24 shown at the left end of the shaft. The cam 24 is pivoted at the point 25 and the shaft is attached thereto at the point 26 below the pivot. The latch 23 is provided with a roller 27 which normally lies behind a shoulder 28 on the cam thereby restraining the shaft in the position shown in the drawings. The upper end of the latch 23 is attached to the armature of an electromagnet 10 whereby when the magnet is energized it is lifted to a position such that the roller 27 releases the cam. The cam then rotates about its pivot 25 in a counterclockwise direction under influence of the spring 22 thereby disengaging all of the bridge members from the contacts of their respective banks. Any sleeve 7, 8, 9 may then be rotated on the shaft to the alternate angular position with respect to the shaft whereupon the shaft may again be moved to the left.

To actuate the shaft to the left against spring 22 an actuating mechanism 6', which is connected to the cam at the point 21 is provided, this mechanism 6' being arranged when energized to rotate the cam in a clockwise direction to the position shown in the drawings where it is again restrained by the roller 27.

The various actuating mechanisms 6', 7', 8', and 9' may be of any desired type but I prefer to employ an actuating mechanism of the type commonly known in the art as a Thrustor. One such mechanism, for example, is shown in United States Patent No. 1,935,432 to Lawrence S. Bourst, issued November 14, 1933. These devices commonly include a piston biased to one position in a cylinder, and arranged to be operated to another position in said cylinder by a suitable motor and pump arrangement whereby a suitable fluid such as oil is pumped from one side of the piston to the other. When the motor of the Thrustor is de-energized, the piston returns under its bias to the initial position, forcing the oil back to the original side of the piston. The rate of movement of the piston in both directions may be suitably regulated by control of the rate of flow of oil. In this way the piston may be positively actuated in either of its two directions in a sufficiently rapid but not abrupt, violent, or jerky, way.

In the drawings a rod 32 actuated by the piston of Thrustor 6' is shown as connected to the cam at the point 21. The corresponding rods of each of the rotating Thrustors 7', 8', 9' are attached to a lever 33 at an intermediate point thereof. This lever is pivoted at its righthand end, whereas at its lefthand end, it is connected by means of a contact carrying member 34 to an arm 35, this arm being attached to the respective sleeves 7, 8, 9 whereby when the corresponding Thrustors 7', 8', 9' are energized, the contact carrying member

34 is lifted causing rotation of the respective sleeve about the shaft 6. The contact carrying members 34 each carry contacts 36 and 37 respectively, which are arranged in circuits for effecting desired control operations which will later be explained. 5

Certain additional auxiliary switches are also provided and are actuated by the movement of the cam 24. One of these comprises the switch 29. This switch is of the tumbler type having a control member or handle 30 which is actuated upwardly and downwardly by prongs 11 projecting from a rack 31. This rack 31 comprises a pair of parallel bars which are connected together by members in the fashion of rungs of a ladder. 15 It is arranged for motion longitudinally of itself upon supports 40 which extend through longitudinal slots in the parallel bars and is actuated by a tail member 38 attached to the cam member 24. This tail member 38 extends through the 20 rack in such a position that when the cam is rotated in its counterclockwise direction it engages one of the rungs of the rack and lifts the rack to an upper position. During this movement the lower prong 11 engages the control member 30 25 of the switch and operates it to the upper position thereby closing the switch. This closing of the switch 29 occurs fairly late in the counterclockwise motion of the cam.

During the clockwise motion of the cam 24 the 30 rack 31 moves downwardly until the upper prong 11 engages the control member 30 of switch 29. The weight of the rack is insufficient to operate the switch and the rack thus remains suspended until roller 27 drops behind shoulder 28. Member 41 attached to latch 23 then engages one of the rungs of the rack with sufficient force to open switch 29. 35

The members 11 are illustrated as prongs for clearness of illustration but may comprise rungs 40 of the ladder, member 30 projecting therebetween and between the side rails of the ladder.

An additional auxiliary switch is indicated at 39. This switch is likewise one of the tumbler type having an actuating member 42 which is straddled by the right bifurcated end of a lever 43. This lever is pivoted at an intermediate point and its left end is attached to the cam 24 at a point at the left of the pivot 25 whereby the lever 43 is rotated about its own pivot in accordance with the motion of the cam. Thus when the cam is operated in a counterclockwise direction the actuating member 42 of the tumbler switch is moved upwardly to close the contacts of the switch. This movement occurs fairly early in the 55 counterclockwise motion of the cam. When the cam is rotated in its clockwise direction member 42 is moved downwardly thereby to open the contacts of the tumbler switch. This opening of the contacts occurs late in the clockwise motion of 60 the cam.

Two additional switches 44 and 45 are also shown, these switches being connected through a lever connection 46 with the armature of latch magnet 10 whereby these switches are opened 65 when the magnet is energized and closed when the magnet is de-energized and roller 27 falls behind shoulder 28 of the cam.

The structure of the switch having been indicated the circuits in which it is connected will 70 now be described. In the first place the various amplifiers 1, 2, and 3 of the transmitter may be of identical construction, the circuits of amplifier 1 only being shown on the drawings. It will be understood, however, that the showing of this 75

amplifier circuit is not complete, but is made only with such detail as to present a complete understanding of my present invention. While my invention is, of course, not limited to any particular type of amplifier, that represented in the drawings comprises a pair of electron discharge devices 47 connected in push pull relation, their anodes being connected to opposite points on a tuned circuit 48, the latter of which is coupled to an output coil 49. The output coils 49 of all of the different amplifiers 1, 2, and 3 are connected in series in a circuit which extends from ground at contact *b* of the left bank of the switch through bridge member 12', output conductors 52 of amplifier 1, bridge member 12'', conductor 53, bridge member 15', output conductors 54 of amplifier 2, bridge member 15'', conductor 55, bridge member 18', output conductors 56 of amplifier 3, and bridge member 18'' to the antenna 4. Thus it will be seen that in the normal position of the switch the output circuits 52, 54, 56 of all of the amplifiers are connected in series between the antenna 4 and ground.

The grids of each of the electron discharge devices 47 of the amplifier 1 are connected to input conductors 57. These input circuits comprising the conductors 57 of amplifier 1, conductors 58 of amplifier 2, and conductors 59 of amplifier 3 are all connected in parallel by the switch and are supplied with oscillations to be amplified from the exciter 5. The circuit for the input to amplifier 1, for example, extends from one side of the output of exciter 5 through conductor 60, bridge member 14' of the switch, output conductors 57, bridge member 14'' of the switch, and conductor 62 to the other side of the output of the exciter. The circuit for the input to amplifier 2 extends from conductor 60 through conductor 63, bridge member 17' of the switch, conductors 58, bridge member 17'' of the switch, conductor 64 and conductor 62. A similar circuit may be traced through bridge members 19' and 19'' for amplifier 3.

Anode potential for the discharge devices of amplifier 1 is supplied through a conductor 65, bridge member 13' of the switch, conductor 66, modulation reactor 67, resistor 68, output of rectifier 69 to ground at 72. The rectifier 69 which is but conventionally indicated on the drawings 50 may be of any suitable type, but is shown as being supplied with three phase alternating current when switch 73 is closed.

Circuits similar to that last described may be traced for each of the other amplifiers through corresponding elements of the switch, these circuits entering the amplifiers through conductors 74 and 75 respectively.

The grid bias potential for amplifier 1 is supplied through a circuit comprising conductor 16, bridge member 13'' of the switch and bias bus 17. A similar connection for the other amplifiers through conductors 18 and 19 respectively may readily be traced on the drawings.

The exciter 5 may comprise any suitable means for supplying high frequency oscillations of appropriate voltage and power to the amplifiers 1, 2, and 3. Polyphase power for energizing the exciter 5 is indicated as supplied through a switch 82 when this switch is closed. Thus the rectangle 5 may also represent suitable rectifying equipment whereby the circuits and instrumentalities for producing the high frequency oscillations are energized. The switches 73 and 82 for supplying energizing potential for the rectifier

69 and exciter 5 are shown as of the electromagnetic type and adapted to be operated to their closed position when switches 44 and 45 are closed, and similarly they are operated to their open position when these latter switches are opened. Manually operated switches 83 and 84 are shown as connected in series with the windings of switches 82 and 73, which switches are closed in the initial starting operation of the apparatus.

The anode circuits of each of the discharge devices 47 of the amplifier 1 include protective relays 85 and 86 which are normally insufficiently energized to close their contacts, but which are operated to close their contacts upon the occurrence of a current of abnormally large magnitude in the anode circuits of the respective discharge devices 47. When so energized the contacts of these relays 85 and 86 remain closed even after the winding of the relay again becomes de-energized or the current therein is reduced to a normal value. This is by reason of a latch device 87 provided on each of the relays whereby it is retained in its closed position. Similar relays are provided in each of the different amplifiers in the manner illustrated and described in connection with the amplifier 1, although for simplicity of the drawings only a single relay 88 is shown in each of the rectangles 2 and 3 representing the other amplifiers.

To describe the operation of my invention let it be assumed that the switches 83 and 84 have been actuated to their closed position and that therefore the switches 82 and 73 are closed thereby to energize the exciter 5 and rectifier 69. Otherwise the apparatus is illustrated in the drawings in its normal operating condition.

Let us now assume that a fault occurs in amplifier 1 which causes energization of one or both of the relays 85, 86 causing these relays to close both of their two pairs of contacts. A circuit is then completed which extends from positive voltage at bus 89 through the upper contacts of the operated relay 85, or 86, conductor 92, auxiliary switch 36 of the respective section of the switch, conductor 93, latch trip magnet 10, back to ground at bus 94. The latch magnet is thus energized and operates its armature immediately to de-energize the actuating magnets of switches 82 and 73 whereby these switches are operated to their open circuit position to remove operating potential from the exciter 5 and rectifier 69. Anode potential and exciting potential are thus immediately removed from the amplifiers 1, 2, and 3.

The armature of latch trip magnet 10, of course, raises the latch member 23 and roller 27 thereby releasing the cam 24 for counterclockwise motion under influence of spring 22. After a slight counterclockwise motion of the cam 24 sufficient to release the different bridge members of the switch from the contacts with which they engage the tumbler switch 39 closes its contacts. This completes a circuit which selects the rotating Thrustor corresponding to the amplifier 1, this circuit extending from ground at bus 94 through switch 39, conductor 95, actuating mechanism of Thrustor 1', conductor 96 and lower contacts of the operated relay 85, or 86. The Thrustor then actuates the lever 33 upward which in turn rotates the sleeve 7 and all of the switch elements mounted thereon about the shaft 6 and to a position such that the bridge members 12', 13', 14' each stand opposite the *a* and *b* contacts of their respective banks and the bridge mem-

bers 12'', 13'', and 14'' each stand opposite the contacts *d* and *e* of its respective banks. Immediately after the initial upward movement of lever 33 produced by rotating Thrustor 7', switches 36 and 37 open. Switch 36 de-energizes the latch trip magnet 10 which releases its armature and permits the roller 27 to fall upon the surface 97 of the cam in which position it has no restraining effect upon the movement of the cam. This 10 holds the armature of latch magnet in such a position that switches 44 and 45 remain open. Switch 37 produces an additional break in a circuit which extends from plus voltage at 98 through the different switches 37, switch 29, and actuating mechanism of the Thrustor 6' to the negative side of the source at bus 94. This prevents energization of Thrustor 6' prior to completion of the rotary motion of the section of the switch corresponding to the amplifier in which 20 the fault occurred. This break in the circuit produced by switch 37 is again closed by switch 36 engaging its upper contacts when the Thrustor 7' has substantially completed its upward motion. Also when the cam 24 has substantially completed 25 its counterclockwise motion, switch 30 closes thereby completing the last traced circuit for the actuating mechanism of the main Thrustor 6'. This Thrustor now applies force through rod 32 rotating the cam 24 in the clockwise direction 30 thereby operating the shaft 6 to the left and moving all of the bridge members into engagement with the contacts standing opposite thereto.

As the cam approaches its final position switch 39 opens thereby de-energizing the rotating 35 Thrustor 7'. The rack 31 moves downwardly until it is supported by control handle 30 of switch 29 its weight not being sufficient to actuate the toggle of this snap switch against its spring bias. Shortly thereafter roller 27 drops behind the 40 shoulder 28. In dropping member 41 carried by latch 23 engages a rung of the ladder forcing it downward and opening switch 29. This de-energizes the main Thrustor 6'. The actuating magnets for switches 82 and 73 are now energized through switches 45 and 44 respectively, whereby 45 the exciter 5 and rectifier 69 are again supplied with operating potential.

Amplifier 1 is now, however, completely removed from the circuit whereas amplifiers 2 and 3 are connected for operation. This will be seen from an inspection of the drawing wherein conductor 65 which formerly supplied anode potential to discharge devices 47 is now connected through bridge member 13' to ground at contact 50 *a* of the corresponding bank of the switch. Similarly conductor 76, which formerly supplied bias 55 potential to the grids of the amplifier, is now connected through bridge member 13'' to ground at contact *d* of the respective bank. Output conductors 52 of amplifier 1 are now open circuited at the contacts *f* and *c* of the switch bank with which they are connected; and the input conductors 51 are now disconnected from the exciter 50 and instead, are grounded at contacts *a* and *d* 60 of the bank with which they are connected. Thus, this amplifier is completely removed from the circuit and the operating potentials being removed therefrom, it may be entered by an operator for the purpose of effecting repairs.

70 Since the two sections of the switches corresponding respectively to the amplifiers 2 and 3 are now in the same position as formerly, these amplifiers are in condition for normal operation, the only change in their circuits residing in that 75 the series connection of their output coils with

the antenna 4 no longer includes the output coil 49 of amplifier 1, a short circuit comprising conductor 99 having been substituted instead, this conductor extending between contacts *a* and *d* of the lefthand bank of the switch.

For the purpose of clarity this antenna circuit will again be described. It now extends from the ground at contact *b* of the left bank of the switch through bridge member 12', to contact *a*, conductor 99, contact *d*, bridge member 12'', contact 10 *e*, conductor 53, bridge member 15', output circuit 54 of amplifier 2, bridge member 15'', conductor 55, bridge member 18', output circuit 56 of amplifier 3, and bridge member 18'' to antenna 4.

15 Thus the equipment is again in readiness for operation. Had the fault occurred in either of the other amplifiers, a similar cycle of operations would have been completed to remove the respective amplifier and to re-establish connections for the remainder of the amplifiers. Similarly, two or all of the amplifiers may be removed in the event that faults occur therein.

Let us assume now that it be desired to restore the amplifier 1 to service after it has been removed in response to a fault. Each of the latch devices 87 is shown as provided with a handle whereby the armature of the respective relay may be released to open its contacts. This having been effected, the operator may then operate switch 102 to its closed position, thereby directly energizing the latch trip coil 10. This trip coil immediately opens the switches 44 and 45 to remove operating potential from the exciter 5 and rectifier 69 thereby to de-energize all of the amplifiers. Cam 24 is released by roller 27 and completes its cycle of operations. Since, however, relays 85 and 86 are now de-energized, the rotating Thrustor 7' is de-energized whereupon the rod 32 actuated by the Thrustor 7' again lowers under bias of the Thrustor and additional spring pressure, if desired, causing the sleeve 7 to be rotated to the position shown in the drawings. When this rotation is substantially completed switch 37 closes its break in the circuit for the main Thrustor. Switch 29 is also actuated as previously described to complete this circuit. The main Thrustor then rotates the cam 24 in the clockwise direction until the roller 27 again drops behind the shoulder 28 when it becomes de-energized. The switch is then restored to the position shown in the drawings and all of the amplifiers are in their normal operating condition.

Any desired means for modulating the oscillations amplified by amplifiers 1, 2 and 3 may be 55 employed. This means is illustrated on the drawings by the rectangle 130 which may represent a conventional Heising modulator whereby the voltage on modulation reactor 67 is varied in accordance with signal currents produced by microphone 131.

Of course, if, in a particular application of the switching scheme provided in accordance with my invention, as, for example, in connection with the grid circuits of vacuum tubes it be desired to 65 shorten the grid leads leading to the switch, then switches of a suitable type, for example, knife blade switches may be employed. Such switches may be placed directly in the apparatus unit and controlled from a corresponding sleeve 7, 8, 9 of 70 the isolation switch through a suitable lever mechanism.

In Fig. 2 of the drawings I have shown a side view of that section of the switch which corresponds to amplifier 3, the remaining sections 75

being, of course, substantially identical. The rod 6 is shown mounted in a suitable framework 103 and is biased to the right by means of the spring 22 previously referred to. Sleeve 9 is also more clearly shown in this figure, the cross-arms 18, 19, and 20 being attached thereto by disks 104 arranged on opposite sides thereof and bolted together in a manner yet more clearly to be described in connection with the other figures. 10 Conducting bridge assemblies 18', 18"; 19', 19"; 20', 20", are shown mounted upon the ends of these cross-arms in engagement with their respective contacts *b* and *c*, and *e* and *d*.

The manner of assembly of the shaft 6, sleeve 15 9, cross-arms, and bridge assemblies may better be understood from Figs. 3 to 6 inclusive. Fig. 3 shows that section of the shaft 6 extending through the portion of the switch shown in Fig. 2, the end of the shaft being attached by a suitable screwthread and nut arrangement 105 to a rod 106 which is attached to and biased by the spring 22. On the rod 6 is mounted the sleeve 9 which is broken away to indicate length, this sleeve having securely attached thereto the arm 25 35 by which it may be rotated. This arm is securely attached to a collar 108 which is riveted to the sleeve 9 and which has an outer ball race 109 seated therein. This ball race aligns with inner ball race 110, the latter being mounted 30 on the rod 6. An additional collar 111 serves as a spacing member for retaining the ball races within the collar 108. The opposite end of the sleeve 9 is undercut at 112 to fit over a collar 113 which is arranged between the end of the 35 sleeve 9 and an additional collar 114 which is securely attached to the shaft 6. Thus the sleeve 9 is held securely in its longitudinal position upon the shaft 6 but is arranged for free rotation thereon.

40 Figs. 4 and 5 show the method of attachment of the cross-arms to the sleeve 9. Each sleeve has mounted upon it a flat-sided member 115 which is held securely in place upon the sleeve by means of the set screw 116 shown in Fig. 5. 45 The cross-arms each comprise a pair of non-conducting bars 117 which extend in parallel relation and are bolted to the opposite sides of the member 115 by means of bolts 119 extending through disks 104 on opposite sides of the two bars, these bolts engaging the opposite square sides of the collar 115.

Fig. 4 is a sectional view on the line 4—4 of Fig. 5 from which consideration a somewhat better idea of the arrangement may be obtained.

55 Fig. 6 is a view partially in section showing the bridge assemblies mounted upon bars 117 of the cross-arms. Each of these assemblies comprises a conducting shield 121 which partially houses the flexible contact brushes 122 which 60 engage the stationary contacts 123. These contact brushes 122 are secured within the shield 121 by riveting to an intermediate member 124, which intermediate member is securely fastened to the shield. A screw 125 projects through a 65 clamping member 126 on the opposite side of the members 127 whereby the shield 121 and contacts 122 are securely attached to the cross-arm.

It will be observed that when the switch is in its circuit closing position the brushes 122 engage their contacts with a certain amount of 70 spring pressure. The switches 29 and 39 of Fig. 1 are operated in properly spaced sequence in the cycle of operation to the switch so that this spring pressure is released before any rotation 75 of the respective cross-arm occurs, and is re-

applied only after rotation of the cross-arm is completed. The contacts 123 are shown as provided at the lower ends thereof with corona shields 126' and as supported by non-conducting supports 127 from the framework of the switch. 5 The holes 128 are provided in each of the contacts for the purpose of making electrical connections therewith in any suitable manner.

Fig. 7 is an end view of the switch showing the arrangement of the contacts, cross-arms comprising bars 117, disks 104, member 115, and sleeve 9, together with the contact assemblies 121. 10

Fig. 8 is an end view of the equipment on line 8 of Fig. 2 and shows the rotating Thrustor 9' 15 which is adapted when energized to operate the lever 33 upward thereby to lift the arm 35 against the bias of spring 129 to rotate the sleeve 9. Lever 33 also actuates contact carrying member 34 which operates switches housed within a container 132 and which are indicated in Fig. 1 as switches 36 and 37. 20

While, by way of illustrating the principles of my invention I have shown means responsive only to particular types of faults to isolate the apparatus unit in which the fault occurs it is obvious that it may be utilized by a person skilled in the art to effect such isolation in response to practically any condition in the apparatus units which renders it desirable to effect such isolation, and that by the term "fault" as used in this specification I have reference to any such condition. 25

While I have described my invention in connection with a radio transmitter, it will be understood that it is not limited thereto, and that I contemplate its use generally in the protection of multiple unit electrical apparatus. 30

While I have shown a particular embodiment of my invention, it will of course be understood that I do not wish to be limited thereto, since many modifications may be made both in the circuits shown and the instrumentalities employed. I contemplate by the appended claims to cover any such modifications as fall within 45 the true spirit and scope of my invention.

What I claim as new and desire to secure by Letters Patent of the United States is:

1. The combination, in a switching scheme, of a plurality of electrical operating units, switching means individual to each of said units for connecting said units to a circuit common to all of said units, common actuating means for said individual switching means, and individual actuating means therefor, said common actuating means being responsive to a fault in any of said units to operate all of said individual switching means to disconnect individually each of the different units from said circuit, and means responsive to the fault to operate the actuating means individual to the unit in which the fault occurred to alter the respective individual switching means, and subsequently to actuate said common actuating means to connect the other of said units to said circuit while said one unit in which said fault occurred remains disconnected. 50

2. The combination, of a plurality of operating units connected in operating circuit relation to each other, a unitary switch structure having 70 actuating mechanism therefor, said actuating mechanism comprising an actuating mechanism common to all of said units and a plurality of individual actuating mechanisms, each corresponding to a respective one of said units, means 75

responsive to a fault in any of said units to operate said common actuating mechanism and the individual actuating mechanism corresponding to the respective unit, means included in said 5 unitary switch structure responsive to operation of said actuating mechanisms to interrupt operation of all of said units, to disconnect said unit in which the fault occurred from operating circuit relation with the other of said units, and 10 to reconnect the other of said units for operation.

3. The combination, in a switching scheme, of a plurality of electrical operating units, switching means individual to each of said units for connecting said units to a circuit common to 15 all of said units, each of said switching means having an open circuit position and a closed circuit position, means responsive to a fault in any of said units to operate all of said switching means to open circuit position, means operative 20 while said switching means are in the open circuit position to alter the condition of the switching means corresponding to the unit in which the fault occurred to disconnect said unit from said circuit when said switching means are operated to the circuit closed position, and means 25 to operate all of said switching means to the circuit closed position.

4. The combination, in a switching scheme, of a plurality of electrical operating units, switching means individual to each of said units for connecting said units to a circuit common to all 30 of said units, means responsive to a fault in any of said units to operate all of said switching means to disconnect individually each of the different units from said circuit and again to operate all of said switches to closed circuit position, and means responsive to said fault in one of said units to alter the condition of the respective switching means in such a way that when said 35 respective switching means is operated to its closed position said one unit is disabled by said switching means.

5. The combination, in a switching scheme, of a plurality of electrical units connected in operating circuit relation with each other, each unit including a switch, means in each unit to actuate the respective switch in response to a fault in the corresponding unit, means responsive to a fault in any of said units to actuate all of said switches, 45 and means to coordinate the actions of said different actuating means in such a way that in response to a fault in any unit said unit is disconnected from said operating circuit relation with the other units and an operating circuit for the 50 other units is completed through the unit in which the fault occurred.

6. The combination, in a switching scheme, of a plurality of electrical units electrically connected together, each unit including switching means, 60 said switching means comprising a movable switch member and stationary contacts cooperating therewith, means responsive to a fault in any of said operating units to actuate all of said members to open circuit position, to alter the switching means in the unit in which said fault occurred in such a way that when said member is again actuated to closed circuit position it disengages certain of the contacts with which it 65 previously engaged, and subsequently to actuate all of said members to closed circuit position, and means including circuit connections through said contacts whereby after operation of said fault responsive means the unit in which said fault 70 occurred is disconnected by said member from

the other of said units and the other of said units remain connected together.

7. The combination, of a switch actuating member adapted for longitudinal movement, a plurality of movable contact members carried thereby arranged for substantially simultaneous longitudinal movement therewith from circuit closed position to circuit opened position and also to rotate thereon, means to operate said actuating member to move all of said contacts 10 longitudinally thereof from one of said positions to the other, and means selectively to rotate any of said contact members while all of said contact members are in the open circuit position.

8. The combination, of a switch actuating 15 member adapted for longitudinal movement, a plurality of movable contact members carried thereby arranged for longitudinal movement therewith and also to rotate thereon, stationary contacts cooperating with each of said movable 20 contact members, apparatus units corresponding to each of said movable contact members, said units being connected in operating circuit relation thereby, means responsive to a fault in any of said apparatus units to operate said actuating 25 member to move all of said contact members longitudinally thereof selectively to rotate the contact member corresponding to the unit in which the fault occurred, and subsequently to return said actuating member to its original position, 30 and means including circuit connections whereby said unit in which said fault occurred is removed from said circuit relation by the respective movable contact member after operation of said fault responsive means.

9. The combination, of a switch actuating member adapted for longitudinal movement, a plurality of movable contact members carried thereby arranged for longitudinal movement therewith and also to rotate thereon, stationary 40 contacts cooperating with each of said movable contact members, a plurality of apparatus units, each of said units including an electron discharge device, and each unit corresponding to a different one of said movable contact members, means 45 comprising said contact members to connect said discharge device in operating circuit relation and to supply operating voltage thereto, and means responsive to a fault in any of said apparatus units to operate said member to move all of said 50 contact members longitudinally thereof, selectively to rotate the contact member in which the fault occurred and subsequently to return said member to its original position and connections whereby said operating voltage is removed from 55 the discharge device of the unit in which said fault occurred by said rotated member and said unit is disconnected from circuit relation with the other units.

10. In combination, a plurality of electron discharge apparatus units connected in operating circuit relation, means to supply operating voltage to each of said units, means responsive to a fault in any of said units to remove operating voltage from all of said units, to disconnect said 60 unit in which said fault occurred from operating circuit relation with the other of said units and subsequently to connect said other of said units for operation and means to reoperate said last means to reconnect said unit in which said fault 65 occurred in operating circuit relation with the other units.

11. In combination, a plurality of amplifiers, each of said amplifiers having an output, means connecting said outputs in series, means respon- 75

5 sive to a fault in any of said amplifiers to de-energize all of said amplifiers, to disconnect said amplifier in which the fault occurred from said series connection, to establish an output connection for the other of said amplifiers and to re-energize said other of said amplifiers.

10 12. In combination, a plurality of amplifiers, means connecting said amplifiers in operating circuit relation to each other, means responsive to a fault in any of said amplifiers to de-energize all of said amplifiers, to disconnect the amplifier in which said fault occurred from operative relation with said other amplifiers, and to reconnect the other of said amplifiers in operating circuit 15 relation with each other, and means to operate said last means to restore said amplifier in which said fault occurred to operating circuit relation with the other amplifiers when said fault has cleared.

20 13. In combination, a plurality of electrical apparatus units, a switch structure, said switch structure comprising a shaft arranged for longitudinal movement, a plurality of contact members corresponding respectively to each of said apparatus units individually mounted for rotation on said shaft and for movement longitudinally of said shaft, stationary contacts cooperating with said contact members, connections through said contact members and respective stationary contacts whereby said units are connected in electrical circuit relation, means responsive to a fault in any of said apparatus units to operate said shaft longitudinally to release said contact members from said contacts, to rotate the contact members corresponding to the unit in which said fault occurred and then to return said shaft to its original position, and connections whereby said one unit is isolated from circuit relation with said other of said units when 35 said shaft is returned.

40 14. In combination, a plurality of electrical apparatus units, a switch structure, said switch structure comprising a shaft arranged for longitudinal movement, a plurality of contact members corresponding respectively to each of said apparatus units individually mounted for rotation on said shaft and for movement longitudinally of said shaft, stationary contacts cooperating with said contact members, connections through said contact members and respective stationary contacts whereby said units are connected in electrical circuit relation, means responsive to a fault in any of said apparatus units to operate said shaft longitudinally to release said 45 contact members from said stationary contacts, means responsive to said movement of the shaft to rotate the contact members corresponding to the unit in which said fault occurred and then to return said shaft to its original position, and 50 connections whereby said one unit is isolated from said other of said units when said shaft is returned.

60 15. The combination, in a high frequency ap-

paratus, comprising a plurality of units connected in operating circuit relation of a relay associated with each unit, means associated with each unit responsive to a fault of predetermined character in said unit to operate said relay, and means responsive to operation of any of said relays to deenergize all of said units, to disconnect said one unit from the other units while said units are deenergized, and again to energize the other of said units while said one unit remains de- 10 energized.

15 16. In combination, a plurality of electron discharge apparatus units operating at high frequency, said units being connected in a common high frequency circuit extending through all of said units, and means responsive to a fault in any of said units to deenergize all of said units, subsequently to disconnect the unit in which the fault occurred from said common high frequency circuit and to complete said high frequency circuit through the other units both while said units are deenergized, and then to reenergize said other units.

20 17. In combination, a plurality of electron discharge apparatus units operating at high frequency, said units being connected in a common high frequency circuit extending through all of said units, energizing means for each of said units, means responsive to a fault in any of said units to deenergize all of said units, to disconnect the unit in which the fault occurred from said common high frequency circuit and subsequently to reenergize the other units, and means to reoperate said last means to deenergize all of said units, to reconnect the unit in which the fault occurred in circuit relation with the other units while all of said units are deenergized, and then to reenergize all of said units.

25 18. In combination, a plurality of high frequency amplifiers connected in circuit relation with respect to currents amplified thereby, means responsive to a fault in any of said amplifiers to deenergize all of said amplifiers, to disconnect the amplifier in which the fault occurred from the other amplifier, to reconnect the other amplifiers in circuit relation with each other, and to reenergize said other amplifier, and means to reoperate said last means to reconnect the amplifier in which the fault occurred in operating circuit relation with the other amplifier.

30 19. In combination, a plurality of high frequency amplifiers connected in circuit relation with respect to currents amplified thereby, means to energize the different amplifiers for operation, means responsive to a fault in any of said amplifiers to deenergize all of said amplifiers, to disconnect the amplifier in which the fault occurred from the other amplifiers and subsequently to reenergize the other amplifiers for operation, and means to reoperate said last means to reconnect the amplifier in which the fault occurred in operating circuit relation with the other amplifiers.

35 EDWARD A. LEACH.
